Primary Examiner — Mary Ann Calabrese*Assistant Examiner* — Sloan Rozin(74) *Attorney, Agent, or Firm* — Fitch, Even, Tabin & Flannery LLP(57) **CLAIM**

We claim the ornamental design for display screen with icon, as shown and described.

DESCRIPTION

The file of this patent contains at least one drawing executed in color. Copies of this patent with color drawings will be provided by the Office upon request and payment of the necessary fee.

FIG. 1 is a front view of a display screen with icon; and, FIG. 2 is a front view of a second embodiment of the display screen with icon.

The greyscale surface shading of FIG. 2 represents color contrast.

The broken line showing of the display screen is for the purpose of illustrating environment and forms no part of the claimed design.
